The ornamental design for a scanner for X-ray tomography diagnosis apparatus with a nuclear medical diagnostic imaging apparatus, as shown and described.

DESCRIPTION

FIG. 1 is a front, top and right side perspective view of a scanner for X-ray tomography diagnosis apparatus with a nuclear medical diagnostic imaging apparatus showing my new design,

FIG. 2 is a front elevational view thereof,

FIG. 3 is a top plan view thereof,

FIG. 4 is a right side elevational view thereof, a left side elevational view being a mirror image thereof,

FIG. 5 is a bottom plan view thereof,

FIG. 6 is a rear elevational view thereof; and,

FIG. 7 is a reference view showing an article in use thereof.

The broken line showing of the rectangular regions on the rear of the scanner and the bed of the scanner is for environmental purposes only and forms no part of the claimed design.
